(57) **CLAIM**

The ornamental design for a table top charging system for electronic devices, as shown and described.

DESCRIPTION

FIG. 1 is a top perspective view of a table top charging system for electronic devices showing my new design;

FIG. 2 is a bottom perspective view thereof;

FIG. 3 is a front elevational view thereof;

FIG. 4 is a right side elevational view thereof, the left side being a mirror image thereof;

FIG. 5 is a rear elevational view thereof;

FIG. 6 is a top plan view thereof; and,

FIG. 7 is a bottom plan view thereof.

The broken lines shown in the drawings illustrate environmental structure and form no part of the claimed design.
